UNITED STATES PATENT OFFICE.

CHARLES L. GRIGG, OF ST. LOUIS, MISSOURI, ASSIGNOR TO HOWDY COMPANY, OF ST. LOUIS, MISSOURI, A CORPORATION OF MISSOURI.

DESIGN FOR A BOTTLE.

Application filed January 19, 1929. Serial No. 29,684. Term of patent 14 years.

To all whom it may concern:

Be it known that I, CHARLES L. GRIGG, a citizen of the United States, residing at city of St. Louis, in State of Missouri, have invented a new, original, and ornamental Design for Bottles, of which the following is a specification, reference being had to the accompanying drawing, forming part thereof.

Figure 1 is a front view in elevation of a bottle, showing my new design. Figure 2 is a side view in elevation of the same design.

I claim:

The ornamental design for a bottle, as shown.

CHARLES L. GRIGG.
